CLAIM

The ornamental design for a fountain as shown and described.

DESCRIPTION

FIG. 1 is a top perspective view of a fountain showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof;

FIG. 8 is a bottom view thereof;

FIG. 9 is a top perspective view of an alternate embodiment of a fountain showing our new design;

FIG. 10 is a bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top view thereof; and,

FIG. 16 is a bottom view thereof.

The dotted lines represent portions of the fountain that form no part of the claimed design.
